UNITED STATES PATENT OFFICE

2,168,572

PRESSURE ROLL FOR SOUND FILM APPARATUS

Daniel O. Landis, Upper Darby, Pa., assignor to
Radio Corporation of America, a corporation of
Delaware

Application June 30, 1937, Serial No. 151,149

3 Claims. (Cl. 271—2.3)

This invention relates to improved pressure roll for maintaining sound film in frictional contact with and in correct alignment upon a drum carrying the film past a translation point. The device is applicable to sound reproducers, sound recorders, printers, or any other analogous apparatus wherein it is desired to move film over a smooth drum without weaving or wobbling.

In many sound reproducers and recorders the film is moved past the point where the recording or reproduction is accomplished over a smooth untoothed drum, as for example in Kellogg Reissue Patent 19,270 and Loomis et al. Patent No. 2,019,147. As shown in the said Loomis et al. patent, heretofore a solid pressure roller has been used to maintain the film in frictional contact with the drum. I have discovered, however, that when a solid pressure roller is used, if the axis thereof is not in exact alignment with the axis of the drum shaft, there may be a tendency for the film to skew or run off to one side or the other of the drum.

In the present device I avoid this tendency for the film to run to one side of the drum or the other by dividing the pressure roller into a plurality of independent sections, and the tendency of the film to deviate from a strict following of its longitudinal path around the drum is correspondingly decreased.

One object of my invention is to provide an improved pressure roll.

Another object of my invention is to provide a pressure roller which will tend to cause the film to run accurately around a smooth drum.

Another object of my invention is to provide a pressure roller which permits greater manufacturing tolerances than were heretofore permissible.

Another object of my invention is to provide a pressure roller which is simple to manufacture and which is easily assembled.

Other and incidental objects of my invention will be apparent to those skilled in the art from a reading of the following specification and from an inspection of the accompanying drawing, in which:

Figure 1 is a plan view of my improved pressure roller as applied to a film drum,

Figure 2 is an elevation of the pressure roller and film drum as seen from the bottom of Fig. 1, and,

Figure 3 is a transverse section of the pressure roller taken along the line 3—3 in Fig. 2.

As shown in the drawing, the film passes around the drum 10 which may be the sound take-off drum as shown in the said Loomis et al. patent or which may be the drum on which recording is

accomplished as shown in the said Kellogg reissue patent. The film is maintained in frictional contact with this drum by the roller 11 carried on the arm 12 and urged toward the drum by the spring 13. The spring 13 may engage any appropriate fixed member such as the arm 14 shown in Fig. 2.

The drum 10 is carried upon a shaft 15 by which it may be driven as shown in said Kellogg patent or which may carry a viscous damper as shown in the said Loomis et al. patent, the drum in the latter case being driven by the film.

The pressure roller 11 is carried on an appropriate shaft or spindle at 16 passing therethrough and carried by the arm 12.

The pressure roller 11 is sub-divided into a plurality of independent sections as shown in Figs. 1 and 3 and each of these sections is independently rotatable upon the spindle 16, and I have found by experiment that this sub-division of the pressure roller into a plurality of sections materially reduces any tendency of the film to travel toward one edge of the drum or the other if the spindle 16 is slightly out of alignment with the shaft 15.

As indicated at 17, one or more of the rollers may be covered with rubber if so desired.

It will be apparent to those skilled in the art that the sections of the roll 11 may, if desired, be covered with rubber or felt or may be entirely composed of rubber or felt. In the latter case, of course, appropriate bearings should be provided interiorly of the rollers to engage the spindle 16. If desired, some of the rollers may be of metal and some surfaced with rubber or felt or composed substantially or entirely thereof, as shown in the drawing.

It will be apparent, of course, that the specific material used for the roller forms no part of my invention and that any appropriate material may be used.

Having now described my invention, I claim:

1. A pressure roller for film feeding apparatus comprising a plurality of contiguous similar independently freely rotatable sections.

2. In combination, a film feed drum, a pressure roll, and means urging the pressure roll into engagement with said drum, the said pressure roll being sub-divided into a plurality of contiguous independent freely rotatable sections.

3. In combination, a film feed drum, a pressure roll, and means urging the pressure roll into engagement with said drum, the said pressure roll being sub-divided into a plurality of contiguous independent freely rotatable similar coaxial sections.

DANIEL O. LANDIS.
